UNITED STATES PATENT OFFICE

145,498

DESIGN FOR A COMBINED FILM AND SOUND PROJECTOR

Wallace W. Ward, Bloomfield, N. J., assignor to
Universal Camera Corporation, New York,
N. Y., a corporation of New York

Application October 10, 1945, Serial No. 122,720

Term of patent 14 years

(Cl. D61—1)

To all whom it may concern:

Be it known that I, Wallace W. Ward, a citizen of the United States and a resident of the county of Essex, city of Bloomfield, State of New Jersey, have invented a new, original, and ornamental Design for a Combined Film and Sound Projector, of which the following is a specification, reference being had to the accompanying drawings, forming part thereof, in which:

Fig. 1 is one side elevation of a combined film and sound projector embodying my design.

Fig. 2 is a front elevation of the same.

Fig. 3 is a rear elevation of the same.

Fig. 4 is the other side elevation of the same.

Fig. 5 is a plan view of the same.

The belting connecting the reel arms has been partially omitted from Figs. 2 and 5 and totally omitted from Fig. 3, for convenience of illustration.

I claim:

The ornamental design for a combined film and sound projector, as shown and described.

WALLACE W. WARD.
